UNITED STATES PATENT OFFICE.

ANDREW H. NEUREUTHER, OF PERU, ILLINOIS, ASSIGNOR TO THE WESTERN CLOCK MANUFACTURING COMPANY, OF LASALLE, ILLINOIS, A CORPORATION OF ILLINOIS.

MACHINE FOR FEEDING AND OPERATING DISKS.

No. 806,359.

Specification of Letters Patent.

Patented Dec. 5, 1905.

Application filed November 9, 1904. Serial No. 232,060.

To all whom it may concern:

Be it known that I, ANDREW H. NEUREUTHER, a citizen of the United States, residing at Peru, in the county of Lasalle and State of Illinois, have invented a certain new and useful Improvement in Machines for Feeding and Operating Disks, of which the following is a specification.

My invention relates to a machine for feeding small circular disks or small sheets or flat pieces into a series of operating cups, dies, or molds, which operating cups, dies, or molds are successively or alternately brought into line with one or more vertically-operating heads, dies, or molds.

It is illustrated in the accompanying drawings, wherein—

Figure I is a section on the line 1 1 of Fig. II. Fig. II is a top view of the machine. Fig. III is an elevation of the feeding device with the threaded part of the forward shouldered cylinder removed to show position of the disks. Fig. IV is a top view of the feeding device.

Like parts are indicated by like letters in all the figures.

A' A⁸ A³ represent the frame of the machine, which is suitably mounted in any desired manner on a bench or standards. The frame is of any convenient form to adapt it for conveniently holding the various portions of the apparatus. As shown it consists of four horizontally-projecting pieces A A⁴ A³ A⁸, attached to vertical piece A'. The parts A⁴ A³ A⁸ serve as bearings for the vertical shaft A', which carries a considerable portion of the driving mechanism. At the left-hand end of A' is attached a vertical projecting part A⁷, which with A' forms the bearing for the horizontal main driving-shaft A⁹, which drives the vertical shaft through the bevel-gears A¹² A¹¹. Shaft A⁹ is driven by means of a pulley A¹³, which is driven by a belt. The pulley may be rigidly connected to the shaft or may be loose on the shaft and operated by any of the usual clutch mechanisms.

On the part A' is formed a vertical shouldered cylindrical part A⁵, which carries the horizontal rotating member B. It is my practice to cast the part A⁵ with the part A'. The rotating member is composed of two similar parts, as shown, suitably fastened together at F. This rotating member B carries a series of projections, on each of which is fastened a

part which carries a cup, die, or molding part 55 B'. The rotating member or turret B is driven by means of rack B², which is attached to its lower end and which meshes with pinion B³, which is associated with friction-disk K, keyed to the shaft A⁹, which is journaled in the piece 60 A', and which friction-disk is similar to that shown in my Patent No. 782,869, granted February 21, 1905. The rotating member or turret B is stopped at proper intervals by means of the pin B⁵, which slides through an aperture in A⁵ and fits into one of the series of sockets in B. The pin B⁵ is attached to the bell-crank lever B⁶ and is operated by means of the toothed cam B⁷, which is rigidly fastened to the vertical shaft A¹⁰. The end of 70 the bell-crank lever B⁶ is held against the cam B⁷ by means of a spring B⁸.

On vertical shaft A¹⁰ between A⁸ and A³ is fastened a cam-wheel C, having cams on its cylindrical surface, on which cam rides a roller 75 C³, which is fastened to a vertically-sliding operating-head C⁶ by means of a pin C⁴. This operating-head C⁶ moves in a slide and slot A⁶, which is a part of A⁸. This operating-head C⁶ is always in alinement with one or more of 80 the series of heads on the turret B in its position when stopped by the pin B⁵.

On the upper end of vertical shaft A¹⁰ is fastened a gear A¹⁴, which meshes into a gear A¹⁵, which in turn meshes into a gear A¹⁶, 85 which is fastened to a smaller gear A¹⁷, (see Fig. IV,) which smaller gear A¹⁷ meshes into a gear A¹⁸. Gear A¹⁸ meshes into two series of gears, (see Fig. IV,) one series A¹⁹ A²⁰ A²³, the other A²¹ A²² A²⁴. The gears A¹⁸, A²⁰, and 90 A²² rotate on pins A²⁵, A²⁷, and A²⁶, attached to part E, and serve only as idler-gears. Gears A²¹ A²⁴ A¹⁹ A²³ are each fastened to the small end of the vertical shouldered cylindrical parts E'. All the gearing thus described 95 serves only to transmit the motion of shaft A¹⁰ to the vertical shouldered cylindrical pins E'. These pins E' are shown enlarged in Figs. III and IV. It will be seen that they consist of a shouldered cylindrical part, the smaller being the upper end, which passes through an aperture in the part E and is then fastened to the gears A¹⁹ A²³ A²¹ A²⁴. The lower end of E' is formed into a screw-thread as shown in Fig. IV. Immediately above the screw-thread cylinders E' pass through the apertures in E², which serve to keep them in proper position and (in the mechanism here represented) 100 105

spaced equal distances apart. It is evident that the spacing, as shown, leaves a space E^4 between these cylinders, which space communicates with the space above E through the 5 aperture E^3 and with the threads and space below E^3 through the aperture E^5 . This space E^4 in my invention is filled, as shown, with either circular or square flat pieces, which may or may not have apertures in the center.

- 10 It is evident from the above description that each of the cylinders E' rotates around its axis and in so doing screws down and advances the pieces in E^4 , as shown at E^6 , and it is evident that for each rotation of the parts E' each of 15 the disks engaged in the thread will advance in accordance with the pitch of the screw, and the one on the lower thread will be released and drop into the cup or head B' , Fig. III; and at the same time the upper end of the 20 thread will engage another disk and separate it from the column of disks in E^4 and start it on the downward journey to the cup, thus dropping one disk at each rotation of E' . Should the pieces or disks to be fed have an 25 aperture through the center, such as is usual in the gear-wheels in a clock, the cylinders E' can be much shorter, and a rod E^6 , Fig. I, can be inserted in the aperture, and several thousands of these disks can be put in the column, 30 as shown at E^4 in Fig. I. The rod E^6 is supported at the top by means of a bracket E^7 , which in turn is rigidly fastened to part E .

I do not wish to limit myself to feeding of smooth-edged disks, but can and do feed such 35 articles as clock-gears, &c.—in fact, any flat pieces, regardless of shape of edges.

- The cylinders E' , the heads B' , and the operating-head C^6 are so timed in relation to each other by means of the cams B^7 and C and 40 the gears A^{14} , A^{15} , A^{16} , A^{17} that E' drops a disk into B' at the same time C^6 performs its operation on the disk directly under it, the turret being locked in its proper position, as before described, by means of the pin B^5 and again 45 released to move to next position when turret is released by cam B^7 withdrawing the pin B^5 . It is evident that the operating-head C^6 and the heads B' can have any suitable shape, governed only by the operation to be performed 50 on the piece, and can have any of the usual devices for ejecting the disks after the operation on them is finished. In the drawings I have shown this as a mold similar to that used

in my Patent No. 782,869. H^2 is the disk or wheel-blank. H is the cavity or mold for the 55 metal. H' is the sprue. H^3 and H^4 are plungers for ejecting the completed work. H^5 is the pivot for the wheel, and H^6 is the pot or metal-supply device used in my Patent No. 782,869, and this, together with mold, &c., described in above-mentioned patent, can be used here; but I do not care to claim the individual features of these here, as they are taken care of in said patent.

From the above description it will be evident 65 that the machine is entirely automatic, as to operate same and keep it working all that is necessary is from time to time to put a column of the pieces in E^4 , the shaft A^9 being driven continuously by a belt from the line-shaft, motor, or other source of power.

It will be understood, of course, that the various portions of my device could be used without the others or in connection with features greatly modified. It will also be understood 75 that cams and turret-moving devices and operating-heads could be greatly modified without departing from the spirit of my invention. In short, I do not wish to be understood as limiting myself to one particular 80 form, arrangement, and grouping of these several features, elements, or parts; but I have presented here that form of a machine that will produce the desired result with the intention of having it taken in a sense as diagrammatic or descriptive of that class of machines which can be produced and any one of which would contain the substance of all or most of my invention.

I claim—

In a machine for feeding and operating upon disks, a device for separating, advancing, releasing and dropping a disk, consisting of an upper and lower support, each having a central aperture surrounded by four concentrically-arranged apertures four vertical shoddered cylinders supported in said apertures, each of which has a screw-thread formed at its lower extremity, which cylinders form a receptacle to receive a stack of superposed disks, and means for rotating said cylinders.

ANDREW H. NEUREUTHER.
